TYPEWRITER COMPANY, OF NEW YORK, N. Y., A CORPORATION OF DELAWARE.

TYPE-WRITING MACHINE.

1,070,747.

Specification of Letters Patent. Patented Aug. 19, 1913.

Original application filed April 17, 1903, Serial No. 153,024. Divided and this application filed February 3, 1909. Serial No. 475,930.

To all whom it may concern:

Be it known that I, BURNHAM C. STICKNEY, a citizen of the United States, residing in Elizabeth, in the county of Union and State of New Jersey, have invented certain new and useful Improvements in Type-Writing Machines, of which the following is a specification.

This invention relates to front-strike 10 platen-shift machines.

This application is a division of my application No. 153,024, filed April 17, 1903, (Patent No. 1,054,470,) on which is claimed the arrangement of ribbon-spools on a frame 15 below the platen carriage, the frame being hinged to the general framework, for the purpose of swinging the spools up into accessible positions when desired, and returning them to normal position under the carriage when the carriage is folded down to bring it into coöperation with the type bars. This divisional application covers the case-shifting features.

The platen is mounted on a carriage which 25 runs upon a support, and the support is mounted to shift up and down to enable different types to print, the carriage being provided with a feeding mechanism which accommodates this up-and-down shifting 30 movement. The shiftable carriage support can also be swung up to move the carriage bodily out of coöperative relation with the types, thereby giving access to the under side of the platen and carriage, as well as to that 35 portion of the typewriting mechanism which lies below the carriage, for the purposes of inspection, cleaning, repair, manipulation, etc.

The carriage-driving spring barrel is 40 mounted to shift with the carriage, which hence need not be formed of two parts hinged together, one part carrying the platen and the other part carrying the rack, which does not shift with the carriage, as 45 heretofore. The letter-feeding dogs are also arranged on the shifting carriage-supporting frame to shift with the carriage, and provision is made whereby the keys upon the framework of the machine may operate said 50 dogs when the frame and carriage are brought down into closed relation with the main framework of the machine to coöperate with the types. The spring-propelled car-

riage is held against being driven by the spring when the carriage is swung up away 55 from the type bars.

Other features and advantages will hereinafter appear, and my invention further consists in certain combinations of devices, features of construction and arrangement of 60 parts, which will be hereinafter fully described and particularly pointed out in the concluding claims.

In the drawings forming part of this specification, Figure 1 is a longitudinal sectional elevation of a front strike writing machine embodying my improvements, one type action being shown in printing position, and the carriage being shown in full lines in normal position, and in dotted lines 65 when tilted up to render the ribbon spools accessible to the operator; the position of the platen when capitals are being written being also indicated by dotted lines below the full-line position. Fig. 2 is a plan; and 70 Fig. 3 is a sectional front view of the machine.

In the several views portions are omitted or broken away for the sake of clearness; and like signs denote like parts.

The framework of the machine comprises side walls 1, whose lower portions may be connected to form a base, and a top plate 2 supported upon said walls; a portion of the top plate being depressed, as at 3, to 85 make room for the paper carriage and its supports.

Forwardly extending type bars 4 are pivoted at their rear ends upon a curved fulcrum-rod 5 mounted in a segment 6, and 90 strike rearwardly against a cylindrical or other platen 7. The segment is radially slotted at 8 to receive the type-bar hubs; and preferably both the segment and the fulcrum-wire incline upwardly and rearwardly, so that the types may strike upon the front side of the platen at a point a little above the horizontal plane of the platen axis. Each type-bar is provided with a lower-case type 9 and an upper-case type 100 10, the former being uppermost when the type bar is in printing position, although this relation may be reversed within the scope of my improvements, and the type-bars may be otherwise mounted. The type 105 bars may be operated by any suitable means,

as for instance pull-links 11 and forwardly-extending levers 12 connected to the links and bearing at their forward ends keys 13; said key-levers being fulcrumed at their rear ends upon a transverse bar 14, and being provided with returning springs 15.

The platen 7 may be mounted by means of an axle 16 upon a carriage which may be of any suitable construction, and is illustrated as comprising side bars 17, united at their rear ends by a longitudinal bar 18, said side bars extending rearwardly from the platen axle; and arms 19 extending downwardly and rearwardly from the platen axle, and connected at their lower ends by a longitudinal carriage-guiding bar 20. Upon a forwardly protruding boss 21 about midway of said bar 20 is mounted a carriage roll 22, which runs upon a horizontal rail 23, provided upon its rear side with a depending flange 24. Secured by screws 25 upon the rear side of this flange are upstanding arms 26, which support a cylindrical rail 27. The carriage-bar 20 is bored longitudinal to slide along upon this rail 27, and is also recessed upon its under side at 28 to pass the arms 26. The members 23 and 27 are connected to form a two-track structure which wholly supports the carriage. A finger 29, secured by the carriage-roll screw 30, hooks under the front edge of the rail 23, thereby coöperating with the bar 20 to hold the carriage upon the rails. A feeding-in roller 31 may be mounted in rear of the platen upon links 32 rising from ears 33 on the carriage-bar 20; and said links may be provided with rearwardly-extending lugs 34 for receiving legs 35 of a paper-shelf 36. From the front side of the bar 20 may project forwardly and upwardly extending arms 37, upon whose forward ends may be hinged at 38 a bail consisting of a pair of upwardly and forwardly extending arms 39 and a platen-scale 40 fixed upon the forward ends of said arms 39 and provided with an apron 41 upon its rear side contiguous to the platen; the upper edge of said scale being below the printing line upon the platen. One or more pressure rollers 42 may be mounted upon an axle 43 mounted at its ends in said arms 39 about midway of their length. Any suitable springs may be provided for the front and rear pressure rollers. So far as my present improvements are concerned, the carriage, paper-feeding means and carriage-supporting and guiding bars or rails may be of any other desired construction.

The flanged rail 23, 24 forms part of a movable frame or support, whereby the paper carriage is enabled not only to run in letter-space direction, but to move also in a direction transverse thereto. This frame or support comprises, in addition to said rail (which need not be flanged in all cases) rearwardly extending arms 44, which are

united at their forward ends by said rail, and a rock-shaft 45, which unites the rear ends of said arms, said rock-shaft being horizontally mounted or hinged upon pintles 46, working in ears 47 projecting forwardly from the front portion of the rear part of the top plate 2. The carriage and its support may be swung together up about said hinges and tilted rearwardly to the dotted line position at Fig. 1, so as to expose the underside of the carriage. Said support may, however, be otherwise formed and otherwise movably supported within the scope of my improvements.

In rear of the type bars and below the platen is mounted upon an axle or axis 48 a pair of ribbon spools 49, 50, said axis being horizontal, and said spools being arranged on edge and side by side. The axis 48, which extends transversely of the machine, that is, from side to side thereof, or from left to right, is mounted in and transfixes the lower end of a forwardly and downwardly extending arm 51, preferably cast integral with the rock-shaft 45, and having an elongated boss 52 for suitably supporting the axis 48. It will be perceived that when in normal position the ribbon spools are inaccessible to the operator, but that when the hinged frame or support is swung up to the dotted line position at Fig. 1, said spools are brought to an accessible position, for convenience in examining or adjusting or attaching the ribbon, or of detaching or replacing the spools, etc. The depressed portion 3 of the top plate is preferably cleft, as at 53, to make room for the spools, which in normal position dip below said depressed portion.

For rotating the spools, I preferably use a pair of pawls 54, 55, operated at every type stroke, and adapted to engage a pair of ratchet wheels 56, associated with the ribbon spools. The latter may be slipped off and onto the axis 48, being retained by thumb-nuts 57; and each ratchet wheel may be connected to its spool by a collar or other device 58, so that one spool with its ratchet may turn upon the axis independently of the other spool and its ratchet. If desired, the member 58 may be splined to the spool, as at 58^a, so as to permit the latter to be slipped off; or the axis 48 may be divided into two lengths, one fixed to and revolving with each spool and ratchet; or any other suitable spool-mounting and revolving means may be employed within the scope of my invention. One ratchet may be omitted, and the other fixed to an undivided axis, and the spools may be alternately clamped to the axis by the thumb-nuts 57, so as to cause the ribbon to wind first on one spool and then on the other.

From one spool the ribbon 59 is led forwardly and upwardly, as at 59^a, then across

the printing point at the front side of the platen, as at 59^b, and then back to the other spool, as at 59^c. At the front side of the platen are provided ribbon-guiding arms 60 and 61, formed at their upper ends with reversely inclined tips 62, 63, the angle of each tip being about 45 degrees, for properly conducting the ribbon across the printing point or field between its ascending and descending portions. Said arms 60 and 61 form part of a ribbon vibrator, being connected at their lower ends by a cross-arm 64, whereby they are supported upon a bent arm 65, which extends backwardly beneath the rail 23 and at its rear end is pivoted by means of a rock-shaft 66 upon bearing-arms 67 and 68, both of the latter projecting forwardly from the rock-shaft 45 of the carriage-supporting hinged frame, and arm 67 overlying the spool-carrying arm 51. By this vibrator, the ribbon may be lifted to cover the printing point at each impression, as at Fig. 1, and depressed to uncover the same; and since the vibrator is mounted upon the hinged frame, it is carried up with the latter when tilted to the dotted-line position at Fig. 1, thus facilitating the reeving of the ribbon from the spools over the guiding arms 62 and 63. Said ribbon-vibrator is operatively connected to carriage-feeding mechanism also mounted upon the hinged carriage-supporting frame and coöperating with a rack 69 on the carriage; said feeding mechanism comprising a detent dog 70 and a feeding dog 71, the latter being normally in engagement with the rack. These dogs are mounted upon a rocker or rock-shaft 72, mounted upon ears 73 and 74 upon the rock-shaft 45; and said rocker 72 is provided with an operating arm 75 which curves downwardly and rearwardly beneath the rock-shaft 45, in position to be operated by a finger or tappet 76 projecting forwardly from the upper end of an upstanding rocker-arm 77, fixed upon a rock-shaft 78 mounted transversely in the base of the machine. Said rock-shaft 78 carries near its ends forwardly directed arms 79, from which is suspended, by means of rods 80, a universal bar 81, extending transversely beneath all of the type-operating key-levers 12, so as to be operated at each type stroke, and completing the train of mechanism whereby the letter feeding movements of the carriage are controlled. The universal-bar and rocker 78 may be returned to normal position by a spring 82; and a returning-spring 83 for the dog-rocker may be coiled about the shaft 72. The connection between the latter and the ribbon-vibrator consists of an arm 84 mounted upon shaft 72, a pull-link 85 connected to said arm and extending forwardly, and an arm 86 connected to said link and mounted upon the vibrator shaft 66. By this means, whenever the dog-rocker is vi-

brated by the keys, the vibrator is elevated to cause the ribbon to cover the printing point; and upon the return of the carriage-feeding mechanism to normal position, said vibrator drops to permit the ribbon to uncover the printing point. 70

The carriage may be propelled by a spring-barrel 87 (Figs. 2 and 3), mounted upon an arm 88, projecting laterally and downwardly from the side-bar 44 of the hinged carriage-supporting frame; and a strap 88^a may connect the spring-barrel 87 to the carriage. By mounting both the spring barrel and the carriage-feeding mechanism upon the hinged frame, the latter is permitted to swing freely up and down, without liability of deranging the carriage-controlling devices, which always maintains their proper relation to the carriage, although by reason of the arm 75 swinging away from the finger 76, the latter cannot of course operate the feeding mechanism when the carriage is tilted up. 85

The ribbon-feeding pawls 54 and 55 may be pivoted at their rear ends upon arms 89 upstanding from the universal-bar rocker 78, and provided with draw-springs 90 connected at their lower ends to the pawls and at their upper ends to the arms 89, whereby the pawls may be held in engagement with the ratchet wheels 56; each pawl being provided with a stop 91, to prevent undue upward movement thereof when the ratchet wheels are swung away from the pawls at the tilting up of the carriage. Behind the pawls is mounted in the side walls of the machine a horizontal shaft 92, having an operating handle 93, and carrying wings 94, 95, the latter being shown as lifting an arm 96 projecting rearwardly from the pawl 55, 95 so as to hold the toothed end of the latter down out of engagement with its ratchet wheel. The shaft may be rocked to depress the wing 95 and allow said pawl to reengage the ratchet-wheel, while the other wing 100 94 rises and lifts an arm 97 provided upon the other pawl, and throws the latter out of engagement, whereby the feed of the ribbon is reversed. Any other suitable ribbon-feeding and reversing ribbon may be employed, and the ribbon spools may be otherwise disposed within the limits of my invention. Preferably advantage is also taken of the hinging of the carriage-support, to enable the latter to be shifted up and down to 115 enable different types to print. Normally the carriage and platen are in an elevated position, as seen in full lines at Fig. 1, thereby enabling the lower-case types 9 to print; while by depressing the carriage and 120 platen (the latter in its depressed position being indicated by a dotted circle at Fig. 1), the upper-case types 10 are enabled to print. The downward movement of the carriage is limited by a pair of adjustable stops 98, and 125 130

its upward movement by a pair of stops having the form of hooks 99 which overhang lugs 100 projecting forwardly from the carriage-supporting rail 23 at the ends thereof. A spring 101, Fig. 1, sustains the carriage and hinged frame normally against the hooks 99, said spring being caught at its upper end over a pin 102 projecting from the side wall of the machine, and at its lower end being caught in a lever 103, which is fulcrumed at its rear end upon a shoulder-screw 104, and is provided between its ends with a vertical thrust-rod 105, which is guided at its upper end in an eye 106 formed in the depressed portion 3 of the top plate, and contacts with a boss 107 formed upon the under side of the side arm 44 of the hinged frame, thereby supporting the latter. A stop-pin 108^a, overlying the lever 103, prevents undue upward movement of the latter when the carriage is tilted up. The lever 103 is provided with a key 104^a, by pressure upon which the pull of the spring 101 may be overcome, and the lever 103 and rod 105 carried down, permitting 25 carriage and hinged frame to drop and rest upon the screw-stops 98.

The hooks 99, which extend through eyes 105^a in the top plate 3, are fixed upon a rock-shaft 106, whereby they may be vibrated forwardly to release the hinged frame and carriage, to permit the latter to be tilted up; said rock-shaft being provided with a returning spring 107, and being mounted in eccentric-nuts 108, by the adjustment of which the hooks 99 may be elevated or lowered so as to position the platen with accuracy. It will be noted that the hinge 46 of the carriage-supporting frame is in rear of and below the platen, so that the latter may 40 shift downwardly and forwardly in a direction agreeing substantially with the tip of the type-bar segment 6, the forward movement being in this instance, however, very slight.

At Fig. 3 it will be noted that the ribbon comes up in direct paths from the spools to the front side of the platen, and that the ribbon-guiding arms 60, 61 are widely separated, so as to expose to view somewhat more than one of the major divisions upon the platen scale, so that at least one of the whole numbers marked upon the platen scale is always visible to the operator between said arms, and he can readily determine at what point the carriage is standing, an index 109 being preferably formed upon the cross-bar 64 for this purpose. The type-guide has a type-opening 110 above the platen scale, and arms 111 and 112 extending laterally and downwardly from said opening, in a manner to leave exposed all of the platen scale which is visible between the ribbon-guiding arms 60 and 61; said type-guiding arms being connected at their

bases by a bar 113, and the type-guiding frame being secured upon the depressed portion of the top-plate 3 by arms 114 and screws 115. At Fig. 1 it will be seen that the type-guiding frame is tipped rearwardly 70 and substantially parallel with the plane of the type bar pivots.

Wide variations in the construction and operation of the different mechanisms may be resorted to within the scope of my invention; and portions of my improvements may be used without others.

The application No. 153,024, filed April 17, 1903, contains claims covering ribbon devices, and the present application is intended 80 to cover platen shifting and correlated devices all independently of the ribbon devices.

I do not claim to be the first inventor of an up-and-down shifting platen. Certain of my improvements, however, are applicable 85 where the platen shifts up and down, the exact direction of such movement being immaterial. In using the term "vertically" in such claims as cover said improvements, I intend to include all movements in an up- 90 and-down direction.

Having thus described my invention, I claim:

1. In a visible-writing typewriting machine in which the type-bars swing upwardly and rearwardly to the platen, the combination of a main frame, a laterally-movable platen carriage, and a shift-frame which entirely supports the carriage and is pivoted to the main frame to swing up and down to 100 place the platen in different printing positions, said shift-frame being connected to the main frame by separated pivots located in rear of the platen and parallel therewith, substantially as set forth.

2. In a typewriting machine in which the type-bars swing upwardly and rearwardly to the platen, the combination of a laterally-movable platen-carriage, a main frame, a rigid shift-frame provided with the carriage-supporting track along its front side, the shift-frame being pivotally connected to the main frame by two pivots at its rear, and an escapement device supported on the shift-frame between the pivots thereof.

3. In a front strike writing machine, the combination of a series of rearwardly-striking types, a platen, a platen carriage, a frame whereon said platen carriage runs, said frame being hinged in rear of the 120 platen, a spring-pressed device sustaining said frame, and a stop against which said frame is held by said spring-pressed device, said carriage and frame being movable in opposition to said spring-pressed device.

4. In a front-strike writing machine, the combination of a series of rearwardly-striking type bars, a platen, a platen carriage, a frame whereon said carriage runs, said frame being hinged to shift up and down to 130

enable different types to print, a platen scale supported contiguous to the platen and below the printing point, and an index on said frame to shift up and down with said scale.

5. In a typewriter, the combination of keys, key-operated type-bars, a platen carriage normally in the path of said type-bars and movable to a position out of coöperative relation with the type bars and also shiftable to enable different types to print, and key-controlled escapement mechanism comprising elements connected to the platen carriage to move therewith when the carriage is shifted to different printing positions or moved out of coöperative relation with the type bars.

6. In a typewriter, the combination with types, of a platen, a platen carriage, propelling mechanism for the carriage, and escapement mechanism for the carriage, said platen being normally in the path of type bars and being both shiftable, together with said carriage propelling mechanism and escapement mechanism, to upper and lower case positions, and also movable, together with the carriage propelling mechanism and escapement mechanism, to a position out of the path of the types, said escapement mechanism constructed to be effective to feed the carriage when the platen is in the path of the types.

7. In a typewriter, the combination with a stationary framework, of type-bars, a hinged frame supported on said framework, a platen carriage mounted to travel on said hinged frame and shiftable with the frame to upper and lower case positions, said carriage and frame also being adapted to swing to a position out of coöperative relation to the type-bars, said carriage being provided with a feeding rack, feed-dogs pivoted upon the hinged frame to coöperate with the rack, and type-controlling keys having means to operate said dogs.

8. In a typewriting machine, the combination with types, type-operating keys and a platen, of a carriage for the platen, a frame on which the carriage runs, the platen being shiftable to positions for upper and lower case letters, said frame being hinged to swing the carriage and carry the platen upward out of coöperative relation with the type, a letter-feeding rack on the carriage, and letter-feeding devices on said hinged frame to coöperate with said rack.

9. In a typewriting machine, the combination with types, type-operating keys and a platen shiftable to upper and lower case positions, of a carriage for said platen, a frame on which the carriage runs, said frame hinged to swing the carriage and carry the platen up and out of coöperative relation with the types, a letter-feeding rack on said carriage, letter-feeding devices on

said hinged frame to coöperate with said rack, and means controlled by said keys for operating said letter-feeding devices only when said platen is down in position to coöperate with the types.

10. The combination with rearwardly striking types, a platen, and a two-track structure under the platen, of a platen carriage wholly supported on said track structure, arms extending from said track structure, and means pivotally connecting said arms to the main frame of the machine for an up-and-down shifting movement of said track structure, to enable different types to print.

11. The combination with rearwardly striking types, a platen, and a two-track structure under the platen, of a platen carriage wholly guided by said track structure, arms extending rearwardly from said track structure and hinged to the framework of the machine, and means for swinging said arms and track structure up and down, to enable different types to print.

12. The combination with rearwardly striking types, a platen, and a two-track structure under the platen, of a platen carriage wholly guided by said track structure, arms extending rearwardly from said track structure and hinged to the framework of the machine, means for swinging said arms and track structure up and down, to enable different types to print, and a spring opposing the weight of the platen carriage.

13. In a typewriting machine having a framework, the combination with a platen and types mounted to strike on the front thereof, of a carriage for the platen, a frame on which the carriage runs, said frame hinged to the framework of the machine to permit the frame and carriage to swing upwardly to give access to the under side of the platen and carriage and such portion of the typewriting mechanism as lies below the carriage, and letter-feeding mechanism for said carriage including a key-controlled member upon said hinged frame, and a key-controlled means for shifting the platen, carriage and hinged frame to enable different types to print.

14. In a front strike writing machine, the combination of a series of rearwardly striking types, a platen, a platen carriage, a support whereon said carriage runs, said support shiftable up and down to enable different types to print, and also capable of being swung upwardly to enable the under side of the carriage to be exposed, and means shiftable with the carriage for controlling the longitudinal movement thereof.

15. In a front strike writing machine, the combination of a series of rearwardly striking types, a platen, a platen carriage, a support whereon said carriage runs, said support shiftable up and down to enable differ-

- ent types to print, and stops opposing each other for limiting both the up and down shifting movements of said support, said support being movable to expose the under 5 side of the carriage.
16. In a front strike writing machine, the combination of a series of rearwardly striking types, a platen, a platen carriage, a frame or support whereon said carriage 10 runs, said support shiftable up and down to enable different types to print, and a releasable stop for limiting the upward shifting movement of said support; said support being liftable past said stop sufficiently to 15 give access to the under side of the carriage.
17. In a front strike writing machine, the combination of a series of rearwardly striking types, a carriage, a frame or support 20 whereon said carriage runs, said frame shiftable up and down to enable different types to print, and relatively adjustable stops opposed to each other for limiting the up and down shifting movements of said 25 frame; said frame mounted to swing upwardly to give access to the under side of the carriage, one of said stops movable to permit such upward movement.
18. In a front strike writing machine, the combination of a series of rearwardly striking type bars, a platen, a platen carriage, a frame or support whereon said carriage runs, said frame having a hinge support in rear of the platen, and shiftable up and 35 down to enable different types to print, and a releasable stop limiting the upward shift of the frame and carriage; whereby when said stop is released, the frame and carriage may be tilted upwardly and rearwardly.
19. In a front strike writing machine, the combination of a series of rearwardly striking types, a platen, a platen carriage, a frame or support whereon said carriage runs, said frame having a hinge support, a 40 spring for lifting said frame, a releasable stop against which said frame is pressed by said spring, said frame being compressible to enable different types to print, and being tiltable upwardly and rearwardly, when 45 said stop is released, so as to expose the under side of the carriage.
20. The combination of a carriage, a frame or support whereon the carriage runs, a hinge on which said frame swings, a ease- 50 shifting mechanism for operating said frame, and a releasable shift-stop for said frame, and the latter being liftable when the stop is released.
21. In a front-strike typewriting machine, the combination of a laterally-movable carriage, a shift-frame which supports the carriage and is pivoted to the main frame in rear of the carriage to shift the carriage up and down, a carriage-escapement mecha- 55 nism arranged on the shift-frame, and a 60 part on the main frame to operate said carriage-escapement, with the point of operative connection between said part and said escapement placed sufficiently close to the pivotal axis of the shift-frame, to render the movement of the carriage-escapement substantially the same in either position of the shift frame. 70
22. In a front-strike typewriting machine, the combination with a main frame and a laterally-movable carriage and platen, of a shifting support for the carriage pivoted to the main frame in rear of the platen for shifting the platen to enable different types to print, and an escapement mechanism including a carriage-controlling member mounted on said shifting support to shift therewith. 75
23. In a visible-writing typewriting machine in which the type-bars swing upwardly and rearwardly to the platen, the combination of a main frame, a laterally-movable carriage supporting the platen, a carriage-shift frame which entirely supports the carriage and is pivoted to the main 80 frame in rear of the platen, a part of said frame extending forwardly under the carriage, and a device in front of the carriage for engaging said part to swing said shift-frame substantially as set forth. 85
24. In a visible-writing typewriting machine in which the type-bars swing upwardly and rearwardly to the platen, the combination of a main frame, a laterally-movable platen-supporting carriage, a shiftable support which entirely supports said carriage and is pivoted to the main frame to swing up and down to place the platen in different writing positions, said carriage and support being constructed to allow the 90 carriage to move laterally on the shift-frame beyond the ends thereof, and said carriage having a rack mounted to shift therewith; and carriage-feeding devices mounted to coöperate with said rack at the 95 different positions to which it is shifted. 100
25. In a visible-writing typewriting machine in which the type-bars swing upwardly and rearwardly to the platen, the combination of a main frame, a laterally-movable platen-supporting carriage, and a shift-frame which entirely supports said carriage and is pivoted to the main frame in rear of the carriage to swing up and down to place the platen in different printing positions; said carriage being movable laterally on the shift-frame in front of the pivotal connection between the shift-frame and the main frame, said shift-frame comprising a carriage track which extends laterally 115 beyond the pivots of said shift-frame, to allow a movement of the carriage beyond the ends of the shift-frame. 120
26. In a visible-writing typewriting machine in which the type-bars swing up- 130

wardly and rearwardly to the platen, the combination of a main frame, a laterally-movable carriage, and a shift-frame which entirely supports said carriage and is pivoted to the main frame to swing up and down to place the platen in different printing positions, said shift-frame comprising a carriage track which extends laterally past the pivotal connection of the shift-frame with the main frame.

27. In a typewriting machine in which the type-bars swing upwardly and rearwardly to the platen, the combination of a laterally-movable platen-carriage, a main frame, and a rigid rectangular shift-frame pivoted at its rear portion to the main frame to swing up and down, and comprising a track which entirely supports the carriage and is located wholly in front of said pivotal connection, substantially as set forth.

28. In a typewriting machine in which the type-bars swing upwardly and rearwardly to the platen, the combination of a laterally-movable platen-carriage, a main frame, a rigid rectangular shift-frame having a supporting-track for the carriage along its front, the carriage being wholly supported on said track, and a pair of separate pivots connecting the rear of the shift-frame to the main frame.

29. In a typewriting machine, the combination with a platen and types striking against the front thereof, of a carriage for said platen, a frame or support whereon said carriage travels, said support and carriage shiftable up and down to enable different types to print, a spring or motor for propelling said carriage, said spring mounted on said support to shift therewith, said carriage provided with a rack to shift therewith, and escapement devices for said carriage including means to coöperate with said rack and accommodate such shifting movements thereof.

30. In a front strike writing machine, the combination of rearwardly striking types, a platen, a platen carriage, a rigid frame whereon said carriage runs, and a hinge device supporting said frame in rear of the platen, said frame being connected to said carriage to shift the same up and down to enable different types to print, and to swing the same up to expose the underlying portion of the machine.

31. In a front strike writing machine, the combination of a series of rearwardly inclined striking type bars, an upwardly and rearwardly inclined segment whereon they are pivoted, a platen, a platen carriage having a feed-rack, and a frame whereon said carriage runs, a hinge device supporting said frame in rear of the platen and below the printing point, and said carriage, including said rack, being wholly supported on said frame, said frame and carriage being

shiftable up and down to enable different types to print, and said rack being shiftable with said carriage.

32. In a front strike writing machine, the combination of a series of rearwardly striking type bars, an upwardly and rearwardly inclined segment whereon they are pivoted, a platen, a platen carriage, a frame whereon said carriage runs, a hinge device to support said frame in rear of the platen, said frame and carriage being shiftable up and down to enable different types to print, and a stop limiting the upward shift of the frame and carriage, said stop releasable to permit the frame and carriage to be swung up to render the underlying portion of the machine accessible.

33. The combination of a carriage, a frame whereon the carriage runs, a hinge device to afford a support to said frame, a case-shifting mechanism for operating said frame, and opposing stops for said frame, said frame being liftable out of position for co-operation with the types.

34. In a typewriting machine, the combination with a platen and types mounted to strike on the front thereof, of a carriage whereon said platen is mounted, a frame whereon said carriage travels, said frame hinged upon the framework of the machine to shift up and down to enable different types to print, a carriage propelling device mounted on said hinged frame to shift therewith, and a carriage escapement mechanism including a rack on said carriage and a coöperating device also mounted on said frame to shift therewith; said frame being also liftable away from a position to co-operate with the types.

35. In a typewriting machine having a framework, the combination with a platen and types mounted to strike on the front thereof, of a carriage for the platen, a frame on which the carriage runs, said frame shiftable up and down to enable different types to print, and letter-feeding mechanism for said carriage including a key-operated member to shift therewith; said frame being capable of a swinging movement, together with said carriage and said member of said letter-feeding mechanism, to give access to the under side of the carriage.

36. In a typewriting machine, the combination with a platen and types striking against the front thereof, of an escapement-controlled carriage for said platen, a support whereon said carriage travels, said support pivotally connected with the main frame of the machine to shift up and down to enable different types to print, and a carriage-propelling spring mounted on said support to shift therewith, said support also capable of swinging up, together with said carriage and spring, to expose the under side of the carriage.

37. In a typewriting machine, the combination with a platen and types striking against the front thereof, of a carriage for said platen, a support whereon said carriage travels, said support and carriage shiftable up and down to enable different types to print, said carriage having a rack, escapement devices to coöperate with said rack and accommodate the shifting movements thereof, and a carriage-propelling spring mounted on said support to shift therewith; said support capable of being moved, together with said carriage and spring, up from the body of the machine to expose the under side of the carriage.

38. In a front strike typewriting machine, the combination of a series of rearwardly-striking types, a platen, a platen carriage, a frame upon which said carriage runs, a spring for sustaining said frame and carriage in normal position, said frame and carriage being shiftable together up and down to enable different types to print, and also movable together to expose the under side of said platen.

39. In a front strike writing machine, the combination of a series of rearwardly-striking types, a platen, a platen carriage, a frame or support whereon said platen carriage runs, a stop, and resilient means to hold said frame against said stop, said carriage and frame being movable against the resistance of said resilient means, and a stop opposed to the first stop.

40. In a front strike writing machine, the combination of rearwardly-striking types, a platen, a platen carriage, a frame or support whereon said platen carriage runs, a hinge device affording a support for said frame, a spring, a stop against which said frame is held by said spring, said carriage and frame being movable against the resistance of said spring, and said stop being releasable so as to enable said frame to be lifted to expose the under side of the platen, said carriage being shiftable downwardly from said stop, to enable different types to print.

41. In a front strike writing machine, the combination of rearwardly-striking types, a platen, a platen carriage, a frame or support whereon said carriage runs, said frame being hinged to the framework of the machine, a spring lifting said frame, a stop against which said frame is lifted by said spring, said carriage being shiftable downwardly from said stop, to enable different types to print, said frame being also tiltable upwardly when said stop is released, to expose the under side of the carriage.

42. The combination with rearwardly-striking types in a typewriting machine, of a non-traveling carriage-track frame hinged directly upon the framework of the typewriter, a spring for supporting said frame, said frame being shiftable up and down to

enable different types to print, and being also liftable to expose the under side of the carriage.

43. In a front strike writing machine, the combination of a series of rearwardly-striking types, a platen, a platen carriage, said carriage shiftable up and down to enable different types to print, and also tilttable upwardly and rearwardly to expose the under side thereof, said carriage having a rack that shifts and tilts therewith, and means co-operating with said rack to control the carriage.

44. In a front strike writing machine, the combination of a series of rearwardly-striking types, a platen, a platen carriage, a frame whereon said carriage runs, a hinge device for supporting said frame in rear of the platen, and shiftable up and down to enable different types to print, and also tilttable upwardly and rearwardly to enable the under side of the carriage to be exposed; said carriage having a rack that shifts and tilts therewith, and means co-operating with said rack to control the carriage.

45. In combination with rearwardly-striking types, a platen, a carriage for said platen, a frame or support hinged upon the framework of the machine to shift up and down to enable different types to print, said carriage mounted on said frame and shiftable up and down therewith, and carriage-propelling devices also mounted on said frame.

46. In a typewriting machine having types to strike the front of the platen, the combination with a main frame, a carriage and a platen, said carriage having a feed rack, of an up and down movable shift frame for the carriage pivoted to the main frame in rear of the platen; the carriage and rack being mounted on said shift frame to shift therewith.

47. In a front-strike writing machine, the combination of a series of rearwardly striking types, a platen, a platen carriage, a frame whereon said carriage runs, said frame being shiftable to enable different types to print, and being tilttable upwardly to enable the under side of the carriage to be exposed, and an escapement mechanism including a part shiftable and tilttable with said carriage to control said carriage in all positions thereof.

48. The combination with a platen and types mounted to strike upon the upper front side thereof, of a platen carriage, a feed rack for said carriage, a frame or support, letter-feeding devices including means on said frame to coöperate with said rack; said frame and carriage being shiftable upwardly and rearwardly to enable different types to print, and said rack shiftable with said carriage.

49. In a front-strike writing machine, the

- combination of rearwardly-striking types, a platen, a platen carriage having a feed rack, and a frame or support whereon said carriage runs, said frame being mounted to shift up and down to enable different types to print, and said carriage and rack being mounted on said frame to shift therewith, and feeding devices on said frame to coöperate with said rack.
- 5 50. In a typewriting machine in which the types strike rearwardly on the platen, the combination of a platen, a platen carriage, a main frame, and a shift-frame or support having a pivotal connection to the main frame to swing up and down, said shift-frame comprising a track which entirely supports the carriage and extends at its ends beyond said pivotal connection at each side of the machine, to permit the 15 track-engaging portions of the carriage to pass by said pivotal connection at each side of the machine.
- 10 51. In a typewriting machine, the combination of a platen carriage having a feed rack, and a frame whereon said carriage travels in letter-feeding direction, said frame mounted to shift up and down, to enable different types to print; said carriage and said rack shiftable together with said 20 frame, and said frame and carriage, together with said rack, being liftable out of coöperative relation with the types.
- 15 52. In a front-strike typewriter, the combination of a support, a platen carriage thereon, said carriage and support being movable to bring the carriage into and out of coöperative relation with the type-bars and being also shiftable up and down to enable different types to print, and key-actuated escapement mechanism including a member shiftable to maintain a coöperative relation to the platen carriage in all positions thereof.
- 25 53. In a front-strike typewriter, a support, a platen carriage thereon having a rack, said carriage and support being movable to bring the carriage into and out of coöperative relation with the type-bars, and being also shiftable up and down to enable 30 different types to print, said carriage and rack being fully supported by said support to shift therewith, and escapement devices to coöperate with said rack and including a member on said support to engage said rack 35 at all positions to which the support and carriage are shifted or moved.
- 35 54. In a front-strike typewriter, a carriage support, a platen carriage thereon having a rack, said carriage and support being movable to bring the carriage into and out of coöperative relation with the type-bars, and being also shiftable up and down to enable 40 different types to print, said carriage and rack being fully supported by said support to shift therewith, escapement devices
- 45 to coöperate with said rack and including a member on said support to engage said rack at all positions to which the support and carriage are shifted or moved, and a carriage-propelling spring also mounted on said support to shift therewith.
- 50 55. In a front-strike typewriter, a carriage support, a platen carriage thereon, said carriage and support being movable to bring the carriage into and out of coöperative relation with the type-bars and being also shiftable up and down to enable different types to print, and escapement devices including a member mounted on said support to move therewith, spacing and type-bar keys, and movement-transmitting means coöperating with all the keys to operate the escapement mechanism.
- 55 56. In a front-strike typewriter, a carriage support, a platen carriage thereon having a rack, said support and carriage being shiftable up and down to enable different types to print, said carriage and rack being wholly supported upon said support to move therewith, an escapement member 60 mounted on the carriage support to shift up and down therewith, and a tappet mounted on the machine frame to strike said escapement member and operate the same.
- 60 57. In a front-strike typewriter, a carriage support, a platen carriage thereon having a feed rack, said support and carriage being shiftable up and down to enable different types to print, said carriage and rack being wholly supported on said support to shift therewith, an escapement member mounted on the carriage support to shift up and down therewith, and a tappet mounted on the machine frame to strike said escapement member and operate the same, 65 100 said escapement member movable with said support into and out of position to coöperate with said tappet.
- 65 58. In a typewriting machine, the combination with a main frame, types and a platen, of a carriage for said platen, a rack on said carriage, a frame on which said carriage runs and which wholly supports the carriage and rack, said frame being hinged to said main frame to swing the carriage to 70 carry the platen up and out of coöperative relation with the types, and being also shiftable up and down to enable different types to print, a spring to propel the carriage, and devices on said frame coöperating with said rack to permit the carriage to move for letter feeding.
- 70 59. In a typewriting machine, the combination with a main frame, types and platen, of a carriage for said platen, a rack on said carriage, a frame on which said carriage runs and which wholly supports the carriage and rack, said frame being hinged to 75 swing the carriage to carry the platen up and out of coöperative relation with the 110
- 75 120
- 80 125
- 85 130

- types, and being also shiftable up and down to enable different types to print, a spring to propel the carriage, devices on said frame coöperating with said rack to permit the carriage to move for letter-feeding, and key-controlled means for operating said feeding devices in the different positions to which said frame and carriage are shifted.
60. In a typewriting machine, the combination of a laterally movable carriage, a shift frame pivoted to the main frame and supporting the carriage, and means having one part supported by the main frame and another part supported by the shift frame for controlling the letter feeding movements of the carriage with the point of engagement between said parts sufficiently close to the pivotal axis of the shift frame to permit the effective feeding of the carriage at both shift positions of the shift frame.
61. In a typewriting machine, the combination with a main frame, types and a platen, of a carriage for said platen, a rack on said carriage, a support on which said carriage runs and which wholly supports the carriage and rack, said support being movable to carry the carriage and platen up and out of coöperative relation with the types, and being also shiftable up and down to enable different types to print, and devices mounted on and movable with said support to coöperate with said rack to control the position of the carriage in all positions thereof.
62. In a typewriter, the combination of a platen, a spring-propelled platen carriage having a rack, and shiftable to upper and lower case positions and also movable bodily into and out of coöperative relation to the type-bars, escapement devices coöperating with said rack and movable therewith at the described shifting and bodily movements of the carriage, and key-actuated means to operate said escapement devices during said shifting movements of the carriage, but disconnected therefrom when the carriage is in a position out of coöperative relation with the type bars.
63. In a typewriter, the combination of a platen carriage shiftable to upper and lower case positions, and also movable bodily into and out of coöperative relation to the type-bars, a letter-feeding rack mounted to accompany the shifting and bodily movements of the carriage, a dog-carrier shiftable with the carriage and provided with dogs which remain in coöperative relation to the rack during the shifting of the carriage, and also during said bodily movement thereof, and key-actuated means adapted to coöperate with the dog-carrier when the carriage is in working position.
64. In a typewriting machine, the combination with a main frame, types and a platen, of a carriage for said platen, a rack
- on said carriage, a support on which said carriage runs and which wholly supports the carriage and rack, said support being movable to carry the carriage and platen up and out of coöperative relation with the types, and being also shiftable up and down to enable different types to print, a dog-carrier mounted on the support and provided with dogs to engage with the rack, and key-actuated means for engagement with the dog-carrier when the carriage is in coöperative relation to the types.
65. In a typewriting machine, the combination of a stationary framework, type-bars, a frame, a hinge-device whereby said frame is supported on said framework, a platen carriage mounted to travel upon said frame and shiftable therewith to upper and lower case positions, means upon said frame for controlling the feed of said carriage, and means upon the stationary frame for operating the feeding means; said frame being mounted to swing out of position to coöperate with the type-bars.
66. In a typewriter, the combination of a spring-propelled platen carriage movable bodily into and out of coöperative relation to the type-bars and also shiftable to upper and lower case positions, and a carriage-feed controlling train comprising two members, of which one is operable by the typewriter keys and the other is movable with the platen carriage in the described bodily and shifting movements thereof, said shiftable member of said feed-controlling train being adapted for coöperation with the key-actuated member thereof when the carriage is in working position.
67. In a typewriter, the combination of a platen carriage, means to shift the carriage to upper and lower case positions, said carriage being movable into and out of coöperative relation to the type-bars, a rack on the carriage, a dog carrier coöperating with said rack, and key-actuated means for controlling said dog carrier, said dog carrier having a predetermined relation to the aforesaid key-actuated means for engagement therewith and disengagement therefrom when the carriage is adjusted to its working and abnormal positions respectively.
68. In a typewriter, the combination of a carriage support, a spring-propelled platen carriage mounted to travel on the carriage support, said carriage and support movable into and out of coöperative relation to the type-bars and also movable to different case-shifting positions, an escapement member for said platen carriage, and key-actuated means for operating said escapement member, said escapement member being movable with the carriage bed into and out of position for operation by the key-actuated means.
69. In a typewriter, the combination of a

carriage support, a platen carriage adapted to travel thereon, said carriage support and carriage being movable into and out of co-operative relation with the type-bars, and 5 also being shiftable to different case positions, said carriage having a rack, a dog carrier mounted on the carriage support and provided with dogs to engage the rack, and a rocking key-actuated frame having means 10 for coöperating with the dog carrier.

70. In a typewriter, the combination of a carriage support, a platen carriage adapted to travel thereon, said carriage support and carriage being movable into and out of co-operative relation with the type bars, and also being shiftable to different case positions, said carriage having a rack, a dog carrier mounted on the carriage support and provided with dogs to engage the rack, a 15 rocking frame adapted to be operated at all times by the typewriter keys, and a tappet mounted on the frame and coöperating with the dog carrier.

71. In a front-strike typewriter, a platen carriage having a rack, a dog carrier, a 25 rocking frame, a tappet in coöperative relation with the dog carrier, means to shift the platen carriage and said frame to upper and lower case positions, said frame being also 30 movable to carry the platen out of coöperative relation to the type bars, key levers, a universal bar actuated thereby, and bell crank connections between the universal bar and the tappet.

72. In a typewriter, the combination with 35 type bars, a platen and a carriage, the carriage being movable out of the path of the type bars and being also shiftable to enable different types to print, of feed mechanism 40 shiftable with the carriage and coöperating therewith when the type-bars are operated, and including means to control the platen against displacement in letter-feeding direction when it is moved out of the path of the 45 type bars.

73. In a typewriter, the combination of a platen carriage and platen, said platen being shiftable to upper and lower case positions, 50 said platen and carriage movable bodily into and out of coöperative relation to the type bars, and a train of letter-feed controlling mechanism for said carriage, said letter-feed controlling mechanism comprising both means movable with the platen carriage as the latter is moved, and means upon the framework of the machine to be operated by the typewriter keys, the portion of said letter-feed controlling mechanism which is 55 movable with said carriage comprising means to control the carriage during such bodily movement thereof.

74. In a typewriter, the combination of a platen carriage and platen shiftable for upper and lower case letters, and also bodily

movable into and out of coöperative relation 65 to the type bars, a tension mechanism for said carriage, and a letter feed controlling mechanism for said carriage, said letter feed controlling mechanism comprising means upon the framework of the machine to be 70 operated by the typewriter keys, and also comprising means to hold the platen carriage against movement under the action of the carriage tension devices when said carriage is adjusted to a non-working position. 75

75. The combination with rearwardly striking types and a platen, of a power driven platen carriage including a feed-rack, a frame whereon said carriage runs, said frame being mounted upon the framework 80 to shift up and down to enable different types to print, said carriage, including said rack, being wholly supported on said frame to shift therewith, and letter-feed controlling mechanism including a device mounted 85 wholly on said frame to coöperate with said rack, and also including an operator therefor for acting concomitantly with the types and wholly mounted on the stationary framework of the machine, and also including 90 means to connect said members in a manner to permit the shifting of the first member with the shift frame.

76. The combination with rearwardly striking types, a platen, and a two-track 95 structure under the platen, of a platen carriage wholly guided by said track structure, arms extending rearwardly from said track structure and hinged to the framework of the machine, means for swinging said arms 100 and track structure up and down to enable different types to print, said carriage having a feed-rack, and means being provided for coöperating with said rack to feed the carriage at the type strokes at the different positions to which it is shifted with said track structure. 105

77. In a typewriting machine, the combination with a platen and types mounted to strike on the front thereof, of a carriage for 110 said platen, a frame supporting said carriage, said carriage and frame movable to a position out of coöperative relation with the types, a spring tending to lift said carriage and frame, a key to control the depression of 115 said platen and frame to enable different types to print, and stops to limit the vibration of said frame, said stops comprising one which is movable to release the frame to permit the latter to swing the platen out of 120 cooperation with the types.

78. In a front-strike writing machine, the combination of a series of rearwardly striking types, a platen, a platen carriage, a frame whereon said carriage runs, said 125 frame mounted to be tilted upwardly and rearwardly to expose the under side of the carriage, and also shiftable to enable dif-

ferent types to print, and adjustable oppositely effective stops for limiting the shifting movements of said frame.

79. In a typewriting machine in which types strike rearwardly on the platen, the combination of a platen, a platen carriage, a main frame and a shift-frame or support pivoted to the main frame to swing up and down, said shift-frame comprising a track

10 which entirely supports the carriage and is located wholly in front of said pivotal connection and extends at its ends beyond said pivotal connection at each side of the machine.

15 80. In a typewriting machine in which the types strike rearwardly against the platen, the combination of a platen, a platen carriage, a track device upon which said carriage travels, arms extending from said

20 track device, means pivotally supporting said arms to enable the track device and carriage to swing up from the machine, and means for shifting the track device and carriage to enable different types to print.

25 81. In a typewriting machine in which the types strike rearwardly against the platen, the combination of a platen, a platen carriage, a track device upon which said carriage travels, arms extending from said

30 track device, means pivotally supporting said arms to enable the track device and carriage to swing up from the machine, and means for shifting the track device and carriage to enable different types to print; said track device extending at its ends beyond

35 said arms at the sides of the machine.

82. In a typewriting machine in which the types strike rearwardly against the platen, the combination of a platen, a platen carriage, a track device upon which said carriage travels, arms extending from said track device, means pivotally supporting said arms to enable the track device and carriage to swing up from the machine,

means for shifting the track device and carriage to enable different types to print; said track device extending at its ends beyond said arms at the sides of the machine; said carriage having a rack mounted to shift therewith, and carriage-feeding devices 50 mounted to coöperate with said rack and accommodate the shifting movements thereof.

83. In a typewriting machine having keys and rearwardly striking types, the combination with a platen and a carriage shiftable up and down to enable different types to print, said carriage being also bodily movable out of coöperative relation with the type bars, of a propelling spring movable 60 with the carriage, means to hold the carriage against the tension of said spring in all positions to which the carriage is so shifted and moved, and means to enable the keys to produce letter-feeding movements of the carriage.

84. In a visible-writing typewriting machine in which the type-bars swing upwardly and rearwardly to the platen, the combination of a main frame, a laterally-movable 70 carriage, a shift-frame which entirely supports said carriage and is pivoted to the main frame to swing up and down to place the platen in different printing positions, said carriage and shift-frame being 75 constructed to allow the carriage to move on the shift-frame laterally past the pivotal connection of the shift-frame with the main frame, and said carriage having a rack mounted to shift therewith; and a 80 carriage-feeding mechanism mounted to coöperate with said rack and accommodated to the shifting movements thereof.
